UNITED STATES PATENT OFFICE.

EDWARD DUDLEY LEWIS, OF ELMIRA, NEW YORK, ASSIGNOR TO ELMIRA CREMATORY CO. INC., OF ELMIRA, NEW YORK, A CORPORATION.

METHOD OF AND APPARATUS FOR CREMATION.

1,263,257.

Specification of Letters Patent.

Patented Apr. 16, 1918.

Application filed January 16, 1917. Serial No. 142,637.

To all whom it may concern:

Be it known that I, EDWARD D. LEWIS, a citizen of the United States, and resident of Elmira, in the county of Chemung and State 5 of New York, have invented certain new and useful Improvements in Methods of and Apparatus for Cremation, of which the following is a specification.

The present invention relates to a method 10 of cremation and to a crematory for carrying out such a method, and an object thereof is to consume the fumes and odors to be consumed without the employment of special passage-ways or other appliances exteriorly 15 of the cremation chamber. Another object of the invention is to provide a construction which will be inexpensive to build. A further object of the invention is to provide, in a cremation furnace, a burner adapted to 20 project a flame of maximum length without danger of causing an explosion or smoke.

To these and other ends, the invention consists of certain parts and combinations of parts all of which will be hereinafter described, the novel features being pointed out in the appended claims.

In the drawings:

Figure 1 is a longitudinal section through a crematory constructed in accordance with 30 the present invention;

Fig. 2 is a transverse section; and

Fig. 3 is an enlarged sectional view showing the burner adjusted to a position different from that shown in Fig. 1.

Referring more particularly to the drawings, 1 indicates the chamber for receiving the body within a casket 32 or otherwise. This chamber is formed within a casing constructed in any suitable manner, as for instance, built up of bricks with its top wall formed by transverse beams 2 acting to support the bricks 3 between them, said beams resting on their ends on the side walls. At the front of the chamber a door 4 may be 40 provided through which the body is introduced into the chamber. Extending from the top wall of the chamber, preferably near the door end thereof, is the outlet flue 5 formed in this instance of a short section 6 embedded in the top wall and projecting slightly above the upper surface thereof for engagement by a section 7 which is, in this instance, in the form of a pipe fitting over the projecting portion of the section 6, and 50 preferably having a peep opening 8 in the rear side thereof.

In the rear wall of the chamber 1 a casting 9 is arranged, this casting having a peep opening 10 therein closed by a shutter 11, and also having an opening 12 through 60 which the burner tube 13 projects, the lower wall of the opening 12 serving as a fulcrum on which the tube may swing in a vertical plane, and the casting having a vertically elongated chamber 14 to one side of the opening in order to guide the burner tube 13 in its vertical movement. Stops 15 are provided on opposite sides of the burner tube to limit the inward movement of the latter, and any suitable means may be employed for sustaining the burner tube 13 in its different angular positions. For the latter purpose an adjustable standard 16 may be arranged in the rear of the crematory, and have its upper end loosely engaging with the burner tube. 75

The burner is preferably of the retort type and in this instance has a helical coil 17 which is removably mounted in the tube 13 and is fed at one end by a pipe 18 to which oil is delivered under pressure from a supply pipe 19, a valve 20 controlling the flow. The other end of the coil has an extension 21 lying parallel with the axis of the coil and extending through the coil, the end of said extension being turned upon itself at 22 to 80 provide a nozzle which discharges the flame in the direction of the axis of the coil and also through the coil. There may also be provided an auxiliary nozzle 23 situated slightly in advance of the inner end of the 90 coil and fed by a pipe 24 extending centrally through the coil and connecting with the supply pipe 19, the supply to the auxiliary nozzle 23 being controlled by a valve 25, for increasing fire. 95

For priming the burner, a priming cup 26 is supported by the burner tube 13, and has a discharge 27 to supply fuel to a piece of asbestos 29 arranged within the burner tube beneath the nozzle 27. The burner tube is 100 also provided with an opening 30 in proximity to the wall of the crematory chamber 1 for the reception of a torch 31 which is inverted and introduced through said opening.

In the use of the crematory the door 4 is 105 opened and the body is placed preferably upon the bottom of the chamber 1, say within a casket 32. After the door is closed the burner is started by filling the priming cup 26 and discharging the contents thereof upon the asbestos mat 29, the burner coil 17 being moved rearwardly so that it lies in front of

the mat 29. After the coil has been sufficiently heated, a lighted torch 31 is introduced through the opening 30 and the valve 20 is opened. This permits a flow of gas 5 from the nozzle 22, this gas being ignited and continuing the heating of the coil 17 to vaporize the oil before the nozzle 22 is reached. After the coil 17 has been sufficiently heated, the valve 25 is opened to permit a discharge from the nozzle 23. It has been found that this construction of burner produces an extremely long flame, being of 10 a length to extend from one end of the chamber to and into the outlet pipe 5. The peep hole 8 is utilized to determine when the 15 flame is passing into the flue.

During the first part of the cremation, the flame is directed along the line *x*, Fig. 1, 20 passing above the body to the outlet 5. This line is held until the greater amount of moisture in the body is driven off. As the fumes or odors must pass through the flame in order to reach flue 5, they are consumed and are not driven in advance of the flame 25 through the flue as they would be if the flue were located in the bottom of the chamber 1. After the moist matters are consumed, the flame is directed toward that end 30 of the body which is in proximity or beneath the flue 5 to consume the solid portions at such end of the body, the flame then being slowly moved or shifted so as to consume the solid matters most remotely situated from the burner until the portions in proximity to the burner are reached. In this 35 way the flame is always arranged between the matter being consumed and the flue, and will consume all odors before they reach the flue.

40 While the invention has been shown and described in connection with a cremation furnace for consuming human bodies, it is apparent that it is not limited to such apparatus but may be embodied in any apparatus where it is desired to dispose of consumable matter of any kind.

What I claim as my invention and desire to secure by Letters Patent is:

1. A method of cremation which consists 50 in first drying the body by directing a flame

above and out of contact with the body from one end of the latter within a closed chamber, while permitting the products to escape through the flame from the top portion of the chamber at the opposite end of the body, 55 to consume the fumes and odors therefrom, and then directing the flame upon that portion of the body most remotely situated from the source of the flame, and gradually moving the flame toward those portions of 60 the body situated nearest the source of the flame so as to consume the solid parts of the body.

2. In a crematory, a chamber for the body, a flame producing means mounted above the 65 bottom of the chamber at one end of the latter, and an outlet for the products of combustion leading from the chamber at the end opposite the burner, the intake end of the outlet being situated at the top of the 70 chamber so that a flame from the flame producing means may reach the outlet without contacting with a body in the combustion chamber, and the flame producing means having a flame projection which will extend 75 to the outlet.

3. A crematory as set forth in claim 2, in which the flame-producing means is adapted to swing in a vertical plane in order to direct the flame upon the body. 80

4. A crematory as set forth in claim 2, in which the flame-producing means comprises a burner tube mounted to swing about a horizontal axis, and a burner removably mounted in said tube. 85

5. In a crematory, a chamber for the body having an outlet at the top thereof near one end, and a burner mounted at the other end of the chamber to swing up and down for directing the flame into the chamber, 90 and comprising a coil and two nozzles, one of which receives supply from the coil and discharges on and through said coil in the direction of the axis of the latter, and the other of which receives its fuel independently of the coil and discharges centrally of the latter and in advance of the coil for extending the flame. 95
